SUPPORTING AND RETAINING MEANS FOR
RAILROAD RAILSHarold G. Warr, Park Ridge, Ill., assignor, by
mesne assignments, to Poor & Company, a cor-
poration of Delaware

Application December 19, 1934, Serial No. 758,250

8 Claims. (Cl. 238—306)

This invention relates to means for supporting and retaining a railroad rail in its proper position and includes certain improvements in a railway tie plate of the general class which includes means integral with the base portion of the plate adapted to overlie the upper edges of the base portion of a railroad rail at opposite sides of the rail to limit, rather than entirely prevent, the vertical and turning movements of the rail with relation to the tie plate.

It has been found preferable in some railway track constructions to rigidly secure the tie plates to the supporting cross ties and to loosely attach the track rails to the tie plates. The loose connections between the rail and tie plates permit the rail, during the wave movements thereof, to move vertically of the tie plates without lifting or otherwise displacing the supporting cross ties in the ballast of the road-bed.

The tie plates heretofore used or proposed which include means integral with the plate and overlying opposite edges of the rail base, have involved the use of separately formed members which are usually positioned or wedged between the rail base and one or both of the inwardly projecting flange portions of the tie plate or they have provided projections of but relatively small area which are caused to project over either edge of the rail base at locations spaced longitudinally 30 of the rail by rotating such tie plates about their vertical axis after the rail has been set in place.

The principal object of the present invention is to provide a tie plate having integral inturned flanges which overlie the upper edges of the rail base at opposite sides of the rail for the full width of the tie plate and which are so formed as to permit the rail base to be seated on the plate beneath said flanges without requiring the plate to be rotated or otherwise shifted from its fixed position on a cross tie and which at the same time will provide, when the rail is seated in its operative position on the plate, suitable clearance between the rail base and the inturned flanges of the plate to permit limited vertical movement of the rail base with relation to the plate.

A further object is to provide, in a tie plate of the above character, simple and inexpensive means for maintaining the rail base in its proper position on the tie plate, and which at the same time will assist in securing the tie plate to a supporting cross tie.

In this connection the invention contemplates one or more vertically disposed key members adapted to be driven through openings in the plate and into the cross-tie, whereby the vertical

position of the keys and their frictional engagement with the supporting cross-tie will maintain them in proper position at all times.

The invention is illustrated in two specific embodiments shown in the accompanying drawings, 5

Fig. 1 is a plan view of one embodiment of the invention, showing the tie plate member thereof applied to the top face of a supporting cross tie and showing the base portion of a railroad rail seated in its operative position on the tie plate.

Fig. 2 is a vertical sectional view taken on line 2—2 of Fig. 1 showing the clearance between the top surface of the rail base and the portions of the plate overlying opposite edges of said plate.

Fig. 3 is a sectional view illustrating the manner in which the railroad rail may be seated on the tie plate while the latter is rigidly connected to a supporting cross tie.

Fig. 4 is a sectional view similar to Fig. 2, but illustrating a modified construction.

Fig. 5 illustrates the application of a railroad rail to the tie plate of Fig. 4, and

Fig. 6 is an enlarged fragmentary sectional view of the larger jaw of the tie plate shown in Figs. 4 and 5.

The tie plate shown in Figs. 1, 2 and 3 of the drawings comprises a base portion 10 of the usual width and thickness. It is preferably fastened 30 rigidly to the top of a supporting cross tie 11 so as to prevent movement of the plate on the tie. The plate is provided with four apertures 12 for receiving screw spikes or other suitable fastening devices 13. The key members hereinafter described for retaining the rail in proper position on the plate also assist in securing the tie plate to the cross tie. It is therefore practical, in most installations, to use but two fastening devices 13. When only two such fastening devices are used, they are applied in the apertures 12 at diagonally disposed corners of the plate.

The upper face of the tie plate is provided with upstanding ribs 14 and 15 between which the base portion 16 of the rail is seated when the rail 45 is in its applied position. The space between the ribs is such as to provide a substantial clearance between the rib 14 and the adjacent edge of the rail base when the rail is in its applied position. The said ribs are formed integrally with the plate 50 and extend the full width thereof so that the inner face 17 of the rib 15 will provide a relatively long abutment for one edge of the rail base. The height of the surface 17 of the rib 15 is greater than the vertical edge face of the rail 55

base. The upper ends of the ribs are formed to provide inwardly projecting flanges 18 and 19 which overlie opposite edges of the rail base 16. The under surfaces of both of said flanges are 5 preferably parallel to the inclined top surfaces of the rail base and are spaced from said top inclined surfaces of the rail base, as indicated at 20 (Fig. 2) to permit the rail to move a limited distance vertically of the tie plate without imparting any lifting force to the tie plate and supporting cross tie. The said clearances between 10 the rail base and the flanges 18 and 19 are preferably such that any abnormal vertical or wave movement of the rail will bring the rail base into 15 abutting engagement with the said overlying flanges.

The rail base is maintained in its proper position beneath the overlying flanges 18 and 19 by means of one or more key members 21-21. The 20 key members herein shown are preferably railway spikes of the square shank type but screw spikes may be used if desired. They are driven through the key openings 22-22 and into the cross-tie so that the shank portions of the keys 25 intervene between one edge of the rail base and the inner face 23 of rib 14 of the tie plate. This position of the spikes holds the adjacent edge of the rail base in proper spaced relation to the inner face 23 of the rib 14 and maintains 30 the other edge of the rail base in proper position adjacent the inner face 17 of the abutment 15. The spaced relation of the rib 14 from the adjacent edge of the rail base makes it practical to form the inner face 23 of said rib of less height 35 than the inner face 17 of the rib 15, and thereby form both ribs of substantially uniform external heights. It is desirable, since the keys 21-21 function as additional fastening devices for the tie plate, to form the rib 14 and flange 18 as 40 low as possible in order to permit the spikes 21-21 to extend the maximum distance into the underlying cross tie 11. The vertical position of the key spikes 21-21, together with their frictional engagement with the cross tie 11, removes any 45 possibility of the spikes being displaced by the forces encountered in service. They are protected from the lifting force incident to the vertical movement of the rail by reason of the attaching devices 13 and the position of the flange 18 of 50 the tie plate between the top surface of the rail base and the heads of the key spikes. The vertical position of the key spikes also insures that they will maintain their position even though the spike holes in the cross tie might become worn in a 55 manner to relieve the frictional grip of the tie on the spikes.

In seating the base portion of a railroad rail beneath the tie plate flanges 18 and 19, one edge of the rail base is first inserted beneath the 60 wide flange 18, until the opposite edge of the rail base clears the inner edge of the abutment flanges 19, as indicated in Fig. 3 of the drawings. After the rail base is seated flat on the tie plate, the rail is then moved laterally until the flange 65 19 of the plate projects a suitable distance over the adjacent edge of the rail base. The spikes 21-21 are then driven through the openings in the flange 18 and the base portion of the plate to hold the base of the rail relatively close to the 70 inner face 17 of the abutment 15, but with capacity for free movement of the rail base vertically of the tie plate. The clearance between the rail base and the under surface of the flanges 18 and 19 is uniform at both sides of the rail base so as to limit 75 both sides of the rail base to the same amount of

vertical movement. In order to provide a minimum of clearance between the rail base and said flanges 18 and 19, the flange 19 is made relatively narrow and its inner edge is beveled as indicated at 24. This construction makes it practicable to 5 support the rail base at a relatively low angle while its edge is being inserted beneath the wide flange 18. The inner edges of flanges 18 and 19 extend parallel with the longitudinal edges of the rail base for the full width of the tie plate. It 10 is therefore practical to apply a rail to or remove it from a number of the tie plates simultaneously without disturbing the fixed positions of the plates on the cross ties.

The modified embodiment of the invention 15 shown in Figs. 4, 5 and 6 of the drawings includes a tie plate 10^a whose construction is the same as the plate shown in Figs. 1, 2 and 3 of the drawings except in the form of the long jaw and flange 25 which overlies one edge of the rail base. 20 The various other parts of the tie plate and attaching devices are identical with the corresponding parts of the previously described embodiment. These various parts and devices have been given corresponding reference numerals with 25 the exponent ^a without being re-described in connection with the modified embodiment.

The under surface of the flange 25, instead of being formed with the same inclination as the top surface of the rail base, as shown in the previous 30 embodiment, is formed with surfaces 26 and 27 which extend at angles to each other. The surface 26 may be and preferably is provided with the same inclination as the top surface of the rail base and joins the vertical surface 23^a, the latter 35 of which in all substantial respects is the same as surface 23 of the previous embodiment. The surface 27 of the modified construction inclines at a greater angle than the top surface of the rail base so as to provide more clearance for the 40 rail base while its edge is being inserted beneath the flange 25 as shown in Fig. 5. However, when the rail base is in its operative position, as shown in Figs. 4 and 6, the clearance between the upper 45 edge of the rail base and the line of contact 29 against the surfaces 26-27 of the flange 25 is substantially the same as the clearance 29^a between the opposite edge of the rail base and the overlying flange 19^a.

The rail base 16^a is seated beneath the overlying flanges of the plate and is secured in its operative position on the plate in the same manner as described in connection with the embodiment shown in Figs. 1, 2 and 3 of the drawings.

While the invention is illustrated and described in connection with two specific embodiments, it will be obvious to persons skilled in this art that various changes might be made in the structures of the plates shown without departing from the principles of this invention. It will be understood, therefore, that the invention includes all such changes which come within the scope of the appended claims.

I claim:

1. Supporting and retaining means for a railroad rail comprising in combination a tie plate formed with spaced upstanding ribs defining a seat for the base portion of a rail and formed at their upper ends with inward projections of different widths transversely of the rail, portions of which overlie the upper edges of the rail base in uniform spaced relation to the rail base at opposite sides thereof to provide abutments for limiting, by direct engagement therewith, upward movement of the rail base relative to the plate, 65 70 75 75

and a key member positioned between one vertical edge of the rail base and the adjacent upstanding rib of the plate to hold said edge of the rail base spaced from said rib and to hold the other edge of the rail base against the other of said upstanding ribs.

2. Supporting and retaining means for a railroad rail comprising in combination a tie plate formed with spaced upstanding ribs defining a seat for the base portion of a rail and formed at their upper ends with inward projections of different widths transversely of the rail, portions of which overlie the upper edges of the rail base and in uniform spaced relation to the rail base at opposite sides thereof to provide abutments for limiting, by direct engagement therewith, upward movement of the rail base relative to the plate, and a key member extending vertically between one vertical edge of the rail base and the adjacent upstanding rib of the plate to hold said edge of the rail base spaced from said rib and to hold the other edge of the rail base movably against the other of said upstanding ribs.

3. Supporting and retaining means for a railroad rail comprising in combination a tie plate formed with upstanding ribs defining a seat for the base portion of a railroad rail and formed at their upper ends with inwardly projecting flanges, one being relatively wide and the other relatively narrow, which overlie the upper edges of the rail base and in uniform spaced relation to the rail base at opposite sides thereof to provide abutments for limiting, by direct engagement therewith, upward movement of the rail base relative to the plate, and a vertically disposed key member extending through an opening in the wide overlying flange and the base portion of the plate to hold an edge portion of the rail base movably against the upstanding rib at the other side of the rail; the said key being of sufficient length to extend into the underlying cross-tie.

4. In a supporting and retaining means for a railroad rail, a tie plate member formed with spaced upstanding ribs terminating at their upper ends with inwardly projecting flanges, one of which is relatively wide and the other of which is relatively narrow, adapted to overlie the upper edges of a rail base in uniform spaced relation to said base at opposite sides thereof, the inner edge of the narrow flange being beveled to provide it with a surface which extends downwardly and inwardly toward the base portion of the plate to reduce the effective height of the rib on which said flange is formed.

5. Supporting and retaining means for a railroad rail comprising in combination a tie plate adapted for application to a supporting cross-tie and formed with spaced upstanding ribs one of which is provided with a narrow inturned flange forming a short jaw which overlies one edge portion of the rail base, the other of said ribs having a somewhat wider inturned flange providing a longer jaw which overlies the edge of the rail base at the opposite side of the rail from the first mentioned flange, the inner vertical face of the rib on which the narrow flange

is formed being of greater height than the inner face of the rib on which the wider flange is formed, there being apertures in said wider flange to receive rail-securing key members and the said key members being positioned vertically in said apertures and driven into the underlying cross-tie to secure the tie-plate to said cross-tie.

6. In supporting and retaining means for a railroad rail, a tie plate formed with spaced upstanding ribs thereon one of which provides an abutment for one edge of a rail base and is formed with a narrow inturned flange overlying and spaced from the top portion of said rail base and the other rib having a wider flange overlying and spaced from the top of the rail base at the other side of the rail, a portion of the under surface of said wide rib being inclined at a greater angle than the top surface of the rail base to facilitate positioning the rail base thereunder and having a portion for contact with the rail base which is spaced from the rail a distance substantially equal to the clearance between the opposite edge of the rail base and said narrow flange.

7. In supporting and retaining means for a railroad rail, a tie plate formed with spaced upstanding ribs extending the full width of the plate, one of which provides an abutment for one edge of a rail base and is formed with a narrow inturned flange overlying and spaced from the top surface of said rail base in a plane parallel to said top surface of the base and the other rib having a wider flange overlying and spaced from the top of the rail base at the opposite side of the rail, a portion of the under surface of said wide flange being inclined upwardly toward the inner edge thereof at a greater angle than the top surface of the rail base to facilitate positioning of the rail base thereunder and having a portion for contact with the rail base, during its upward movement thereof relative to the plate, which is substantially equal to the clearance between the rail base and the said narrow flange.

8. In supporting and retaining means for a railroad rail, a tie plate formed with spaced upstanding ribs, one of which provides an abutment for one edge of the rail base and is provided with a narrow inturned flange overlying and spaced from the top surface of said base and the other rib having a wider flange overlying and spaced from the top of the rail base at the other side of the rail, a portion of the under surface of said wide flange being inclined and spaced from the top of the said rail base a distance equal to the clearance between the opposite edge of the rail base and the said narrow flange and provided also with a portion adjacent the inner edge of the wide flange which inclines upwardly at a greater angle than the top surface of the rail base positioned thereunder, there being also a plurality of apertures extending through the wide flange adapted to receive key members adapted to be driven through said apertures and into the underlying cross-tie.

HAROLD G. WARR.
